UNITED STATES PATENT OFFICE.

WILLIAM H. CLEMENTS, OF NUTLEY, NEW JERSEY.

BOX OR TRAY FOR SAMPLE-CASES.

SPECIFICATION forming part of Letters Patent No. 794,451, dated July 11, 1905.

Application filed February 3, 1905. Serial No. 243,980.

To all whom it may concern:

Be it known that I, WILLIAM H. CLEMENTS, a citizen of the United States, residing in Nutley, county of Essex, and State of New Jersey, have 5 invented certain new and useful Improvements in Boxes or Trays for Sample-Cases; and I do hereby declare the following to be a full, clear, and exact description of the invention, such as will enable others skilled in the art to which it 10 appertains to make and use the same, reference being had to the accompanying drawings, and to letters of reference marked thereon, which form a part of this specification.

This invention involves certain improvements in trays or boxes for sample-cases of the kind set forth in United States Letters Patent to Henry Braen, No. 574,130.

The improvements may be applied in the construction of trays and boxes generally, 20 whether with or without covers, and in that connection have for their object to strengthen the tray or box, increase its rigidity and durability, and reduce the cost of manufacture, and in connection with boxes or trays for 25 sample-cases to better adapt them for nesting together in the closed position of the case without their telescoping.

The invention will be found fully illustrated in the accompanying drawings, wherein—

30 Figure 1 is a perspective view of the improved box or tray. Fig. 2 is a transverse sectional view thereof at, say, its middle portion. Fig. 3 is a plan view of the box or tray with one of its end members removed. 35 Fig. 4 is a top plan view of the removed end member; and Fig. 5 is a view, partly in side elevation and partly in vertical section, of a series of such boxes or trays nested together.

The box or tray comprises three separate 40 members—a body member, comprising the bottom and side walls, and two end members, forming the end walls. For the body member a sheet of metal is bent up at right angles parallel to two opposite sides, thereby forming the bottom wall *a* and two side walls *b*. The edges of the side walls are bent outwardly and downwardly, as at *c*, so that a groove *d* is left. 45 This forms a reinforcing-flange along the top of the side wall, which by being hollow by 50 virtue of the groove *d* is not only stronger

than it would be if the flange were turned over and compressed against the side wall, but serves for interlocking the side and end wall in the manner hereinafter described. *e* designates the end walls. Each of these is 55 formed of a piece of sheet metal having its two long edges bent off in the same direction, as at *f* and *g*, at right angles to the body of the metal, the flange *g* being preferably deeper or wider than the flange *f*. The ends of the 60 metal are cut down to a width approximating its body portion, leaving wings *h*, which are bent off at right angles to said body portion in the same direction as the flanges *f* and *g*. The end members thus formed are then as- 65 sembled with the body member of the box or tray, with the wings *h* standing outside of the side walls *b* and the wings *g* under the ends of the bottom wall *a* of the body member, whereupon rivets *i* or other securing means 70 are employed to hold the body and end mem- bers together. The upper edges of the wings *h* are received in the ends of the grooves *d*, being thus not only sheathed, but in part 75 forming an interlocking joint between the end members and the body member.

Constructed in the manner above described the box or tray is strengthened and made more rigid throughout. The flanges *g* act to 80 in a great degree prevent the downward bulging or sagging of the bottom wall *a*. This permits a strong box or tray to be made of some such light and relatively weak material as aluminium and, moreover, reduces the waste of material to the minimum. When 85 the boxes are nested together, as in Fig. 5, the end walls *e*, reinforced by the flanges *f* and *g*, take directly the weight of the boxes and their contents and prevent by their flanges resting on each other any possibility of the 90 boxes telescoping.

Having thus fully described my invention, what I claim as new, and desire to secure by Letters Patent, is—

The combination, in a box or tray, of a body 95 member and two end members formed of sheet metal, said body member comprising a bottom and two side walls, the latter having their top edge portions bent outwardly and forming edge grooves, and said end members forming the 100

end walls and having inwardly-projecting flanges at their bottom edges extending under the ends of said body member, said end members also having wings folded flat against the 5 end portions of the said side walls and projecting into said grooves, substantially as described.

In testimony that I claim the foregoing I have hereunto set my hand this 27th day of January, 1905.

WILLIAM H. CLEMENTS.
